F. M. FURBER

APPARATUS FOR APPLYING LIQUIDS

Filed Sept. 8, 1923

INVENTOR

Ferdinand M. Furber

UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

APPARATUS FOR APPLYING LIQUIDS.

Application filed September 8, 1923. Serial No. 661,682.

To all whom it may concern:

Be it known that I, FREDERICK M. FURBER, a citizen of the United States, residing at Revere, in the county of Suffolk and State 5 of Massachusetts, have invented certain Improvements in Apparatus for Applying Liquids, of which the following description, in connection with the accompanying drawings, is a specification, like reference characters on the drawings indicating like parts in the several figures.

My invention relates to apparatus for applying liquids to various objects, and particularly to means for coating shoe-portions 15 with blacking or other stains.

In the patent in my name numbered 1,311,161 and dated July 29, 1919, is disclosed an apparatus for producing a spray 20 of blacking for application to the marginal edges of soles, in which apparatus a fixed jet-opening, furnished by a hole drilled through a casing-wall, has co-operating with it an adjustable air-nozzle. This nozzle, 25 by its relation to the jet-opening and to the opening of the conduit through which the liquid to be sprayed is drawn, will vary the fineness of division of the particles forming the spray, and to some extent the volume of spray emitted from 30 the jet-opening. The latter effect, however, is slight, and is dependent upon the change of character of the spray-particles, it being impossible to alter one, leaving the other undisturbed. To most efficiently coat 35 various kinds of stock with different substances, and to produce different intensities of color, it is desirable to independently control the quantity of spray and its character. To provide means for thus governing the apparatus is an object of this invention, this 40 being accomplished by changing the relation of the jet-opening to the associated elements. It should also be noted that the fixed jet-opening becomes worn in the use 45 of the apparatus by the attrition of the particles in the stain, and the resulting increase in area disturbs the condition of the spray which adjustment of the apparatus had established. My invention, by the movable 50 jet-opening, overcomes this difficulty.

Since an apparatus of the type of that above indicated depends for its operation upon a partial vacuum produced by the air ejected from the nozzle through the jet-open-

ing, adjacent to the opening of the liquid-conduit, it is important that the chamber in which this action occurs shall be airtight, save for the openings just mentioned. The apparatus of the patent furnishes a joint between the adjustable air-nozzle and the containing casing by a thread upon the upper portion of the nozzle and a cylindrical fit over its lower portion. In manufacture, it is very hard to produce perfect alignment between the threaded and smooth portions, and leakage of air tends to result. To so form the engaging surfaces of the air-nozzle and its casing that an airtight joint shall be produced throughout the length of the nozzle is a further object of 70 my invention.

A particular embodiment of the invention is illustrated in the accompanying drawing,

Fig. 1 being a view in side elevation, with 75 parts broken away, of a sole-blacking machine embodying the present improvements;

Fig. 2, an enlarged vertical section through the spray-producing elements; and

Fig. 3, a perspective view of the bushing 80 containing the jet-opening.

Mounted upon an arm 10 containing a conduit 12, through which air under pressure is delivered from some suitable source, is a casing 14. This casing has at its upper extremity a reduced portion 16, passing through vertical opening in the outer end of the arm and being externally threaded to receive a nut 18 which clamps the casing in place upon the arm. Gaskets 20, 20, 90 interposed between the nut and arm and between said arm and the body-portion of the casing, prevent the leakage of air through the joint between the casing and the arm. 85

Extending vertically through the casing is a passage 22, in which are two lateral openings. One of these, designated by the numeral 24, is near the center of the casing, and the other, 26, near its lower extremity. That first mentioned communicates with the 100 air-conduit 12. The opening 26 is joined to a vertical conduit 28 dipping at its lower end in a receptacle 30 for the liquid which is to be applied. The passage 22 is internally threaded, preferably for its entire length, 105 over a bore of uniform diameter, this thread being engaged by an external thread upon a plug 32, which projects above the top of

the casing. About the plug, opposite the opening 24, is an annular groove 34, which is of such width longitudinally of the plug that it will remain always in communication 5 with the air-opening 24; however the plug may be adjusted along the passage 22. Into the groove 34 opens a transverse passage 36 through the plug, and connected to the passage 36 is an axial longitudinal passage 10 38, the latter extending through a reduced tip 40 upon the body-portion of the plug, furnishing an air-discharge-nozzle, the opening of which lies opposite the liquid-opening 26. The threads of the passage 22 15 and the plug 32 extend both above and below the air-opening 24 and groove 34, and maintain a tight closure against the passage of air between the plug and casing in both directions after it has been forced through 20 the opening 24, confining this to delivery through the nozzle 40. Since the threaded portions are of equal diameter throughout, and are formed upon each of the respective elements by a single operation, the integrity 25 of the joints will be maintained; however the plug 32 may be turned in its adjustment along the passage. This adjustment may be effected by a head or finger-piece 48, the positioned plug being held by a nut 50 30 operating upon the portion of the plug rising above the casing and contacting with the portion 16 of the casing.

Into the lower end of the passage 22 is threaded a bushing 42, located axially of 35 which is a jet-opening 44 alined with the longitudinal passage 38 of the plug. This bushing is removable, to be replaced by another when the opening 44 becomes worn, the change being effected by turning the bushing 40 by engagement with a squared portion 46 at its lower end. Through this replacement, the diameter of the jet-opening may be kept substantially constant. Further, by turning the bushing in the threaded passage 22, 45 it may be caused to move up or down therein, thus changing its relation to the liquid-opening 26 and to the nozzle 40, it being held against displacement by the frictional engagement of the threads. It will be observed that in this adjustment the upper 50 end of the bushing moves across the edge of the liquid-opening 26, thus varying the area of the latter.

To state briefly the well-known action of 55 the organization, air under pressure, forced through the conduit 10, flows by way of the opening 24, passages 36 and 38 and nozzle 40, into a chamber 47, in which the nozzle is situated, and is discharged through the 60 jet-opening 44. By its flow, it produces a partial vacuum in the chamber 47, which causes atmospheric pressure upon the liquid in the receptacle 30, to force this liquid up the conduit 28 and through the opening 26 65 into the chamber 47. Here, meeting the air

from the nozzle, it is atomized, and thrown from the jet-opening as a spray. The rate at which the liquid is drawn through the conduit 28 depends upon the area of the opening 26 where it communicates with the chamber 47, the height of the upper end of the jet-opening 44 above the liquid in the receptacle, and the degree of the vacuum produced in the chamber 46. The fineness of the spray ejected through the jet-opening 70 varies with the distance between the lower extremity of the nozzle 40 and the upper end of the opening 44. The independent adjustment of the plug 32 and the bushing 42 gives a capacity for altering particular relations 75 between the elements without disturbing other relations which may have been established. In this way, there is assured a very exact control of the quantity and character 80 of the spray discharged, to best meet varying conditions in the character of the stock treated, of the stain applied, and in the depth of color to be imparted.

Having described my invention, what I claim as new and desire to secure by Letters 90 Patent of the United States is:—

1. In an apparatus of the class described, a casing having a jet-opening and a liquid-inlet-opening, an air-nozzle delivering to the jet-opening, and means arranged to permit 95 the relation of the jet-opening to the air-nozzle and to the liquid-inlet-opening to be varied.

2. In an apparatus of the class described, a casing having a jet-opening and a liquid-inlet-opening, an air-nozzle variable with respect to the liquid-inlet-opening, and means 100 arranged to vary the relation of the jet-opening to the liquid-inlet-opening.

3. In an apparatus of the class described, a casing having a liquid-inlet-opening, an air-nozzle associated with the casing, and a member containing a jet-opening co-operating 105 with the liquid-opening and air nozzle and being separably mounted in the casing.

4. In an apparatus of the class described, a casing having a liquid-inlet-opening, an air-nozzle associated with the casing, and a member containing a jet-opening and being mounted in the casing to move into different 110 relations to the liquid-opening and air-nozzle.

5. In a blacking apparatus, a casing through which is a passage having a liquid-opening communicating with it, an air-nozzle co-operating with the passage, and a member containing a jet-opening, said member being movable in the passage to vary the effective area of the liquid-opening. 120

6. In a blacking apparatus, a casing through which is a threaded passage having a liquid-opening communicating with it, a threaded plug arranged for movement along the casing-passage and containing an air- 125 passage, and a bushing threaded to engage 130

the extremity of the casing-passage adjacent to the liquid-opening.

7. In a blacking apparatus, a casing through which is a threaded passage having a liquid-opening and an air-opening communicating with the passage, a plug threaded to engage the thread of the passage at opposite sides of the air-opening and containing a passage connected thereto, and a bushing threaded into the extremity of the casing-passage and having a jet-opening.

8. In an apparatus of the class described, a casing provided with a jet-opening, a liquid-conduit connected to the casing, an air-conduit delivering to the casing, and a nozzle having a body-portion, in which is a passage communicating with the air-conduit and terminating in proximity to the jet-opening, said body-portion having

20 threaded engagement with the casing at op-

posite sides of its point of communication with the air-conduit.

9. In an apparatus of the class described, a casing provided with a jet-opening and a passage extending through the casing in alignment with the jet-opening, there being a liquid-opening in the passage adjacent to the jet-opening and an air-opening in the passage at a point removed from the jet-opening, and a plug provided with a passage connecting the air-opening and jet-opening and having threaded engagement with the casing for substantially its entire length therein at opposite sides of the point of communication between its passage and the air-opening.

In testimony whereof I have signed my name to this specification.

FREDERICK M. FURBER.
